CLAIM

The ornamental design for a wall mountable accessory, as shown and described.

DESCRIPTION

In a preferred embodiment, the nature of this product is as an accessory in the form of a towel hook.

FIG. 1 is a left, top, front perspective view of a wall mountable accessory embodying our new design;

FIG. 2 is a front elevational view thereof;

FIG. 3 is a top plan view thereof;

FIG. 4 is left side elevational view thereof;

FIG. 5 is a right side elevational view thereof;

FIG. 6 is a bottom plan view thereof;

FIG. 7 is a rear elevational view thereof; and,

FIG. 8 is a front elevational view of a wall mountable accessory of another embodiment of our new design, the perspective, front, top, left side, right side, bottom and rear views of this embodiment being mirror images of the respective views shown in FIGS. 1-7.

The broken line representations of the mounting structure in FIG. 7 are for the purpose of illustration only, and form no part of the claimed design.
